(57) **CLAIM**

An ornamental design for a combined display and vehicle, as shown and described.

DESCRIPTION

FIG. 1 is a back perspective view of my new design;

FIG. 2 is a back view of FIG. 1; and,

FIG. 3 is a side view of FIG. 1.

The broken lines showing elements of the display on a vehicle in the above described figures are for illustrative purposes only and form no part of the claimed design.
